MANUAL BOOKKEEPING APPARATUS

John E. Rosso, Virginia, Minn.

Application May 24, 1940, Serial No. 337,016

6 Claims. (Cl. 282—29)

This invention relates to improvements in manual bookkeeping apparatus such as set forth in my copending application Ser. No. 226,483, filed August 24, 1938, now Patent No. 2,202,639 dated May 28, 1940.

The principal object of the instant invention is that of providing convenient means for the proper alinement both vertically and horizontally of indicia when applied to one or more blank sheets upon which such indicia is required.

Another object is to provide more conveniently adjustable and accurate means for determining the location both vertically and horizontally of the areas in which such indicia is to be applied.

Still other objects and advantages of the invention will appear in the following description of the invention.

Referring now to the accompanying drawing forming part of this application and wherein like reference characters indicate like parts:

Figure 1 is a broken elevation of the clamping bar side of one of the devices embodying the invention with the line and column guide partly elevated.

Figure 2 is a section on the line 2—2, Figure 1.

Figure 3 is a broken plan view of the slidably adjustable members on the clamping bar with the line and column guide in horizontal position.

Inasmuch as the instant invention resides in improvements in that part of the mechanism associated with the clamping bar it is not considered essential to show a plan of the entire platform of the mechanism, it being deemed sufficient to illustrate the edge view of such board, which is indicated at 1, in Figures 1 and 2, and in this instance it is contemplated to use a relatively thin sheet of rigid board like material suitable for the purpose and resting preferably upon a plurality of rubber supports indicated at 2.

The clamping member or bar in this instance is preferably made of two vertically spaced metal members indicated at 3 and 4, they being held separated as by suitable blocks 5 at either end thereof and attached to same as by screws indicated at 6, and which blocks in conjunction with those indicated at 7 attached below the corners of the board 1 answer as supports for the pivotal connections 9 and 10 at either end of the bar, which in all respects functions identically with the clamping bar illustrated in my copending application supra.

The principal novel feature of this invention residing in the pivotally mounted line and column guide, will first be described in detail. The pivotal support for this guiding member is illus-

trated at 11 and 12 upon opposite sides of the outer wall or side member 13 of the carriage for such guide, and the body of the carriage is illustrated at 14, it being slidably disposed intermediate of the two members 3 and 4 of the clamp bar. The correct alinement of the carriage with the spaced rows of pegs indicated at 15 and fixed to the board 1 is preferably determined as by the spring controlled ball 16 installed within the body 14 of the carriage and which ball automatically retards the movement of the carriage consecutively as the same is slid up and down on the clamping bar.

The member 13 of the carriage is provided with the two upstanding spaced portions 17 which provide bearings for the pivotal connections 11 and 12 of the line and column guide support 18, the guide proper including the members 19, 20, and the wires 21. Intermediate of the spaced members 17—17 extends outwardly and upwardly the member 23 which is formed integral with the member 18 and functions as means for raising the line and column guide to for example the position indicated in dotted lines, Figure 2 of the drawing, or in Figure 1 as it is there shown only partly raised.

The line and column guide comprises the principal supporting member 19 which is preferably formed integral with the angular portion 18 which normally extends up over the clamping bar and forms the connection with the carriage for adjustment thereof, and is designed to lie horizontally on the member 1 for application of the figures upon said sheet through the spaces intermediate of the horizontal and vertical wires 21, the end member 24 of the guide being also preferably integral with the member 19 while the member 20 is preferably of transparent material such as Celluloid or the like through which any indicia upon the sheet receiving the figures may be readily seen. This, of course, is provided, like the members 19 and 24, with through holes 25 in which the wires 21 are strung as desired to form the necessary spacing in which the figures or entry are made manually.

It is to be noted that the body portion 14 of the guide carriage is provided with an extension 26 in which is fixed the thin pointer 27 extending forwardly and just above the member 19 of the line and column guide, and in this relation it at all times remains, it moving with the carriage as the latter is adjusted. This pointer is sufficiently arched to freely pass over the like pointer 28 on the carriage indicated at 29, and this carriage is also slidably longitudinally and

intermediate of the members 3 and 4 of the clamping bar. It is to be noted that both the carriages 14 and 29 are preferably operated as by suitable handle-like members 30 and 31 respectively and in this instance I have shown the adjustment of the clamping bar as being accomplished by the relatively short and neat handle 32 fixed to one of the lower pivotal shafts 10 of the links 33 which adjustably support the clamping bar.

Having thus described my invention, what I claim and desire to secure by Letters Patent is:

1. Manual bookkeeping apparatus comprising in combination a backing board to receive a plurality of separate loose-leaf blank bookkeeping forms perforated along one edge, a row of pegs carried by said board to receive the perforated side of said forms and hold same in predetermined relationship to other forms on the board, a movable clamping bar attached to said board and engageable with said forms upon one side of said pegs, and a combined column and line guide slidably supported by said clamp bar for designating on the other side of said pegs a space in which an entry may be made on any or all of said forms, said column and line guide being arched to extend over said pegs so that it may be moved without contacting said pegs, and including a plurality of spaced intersecting flexible wires between which indicia may be manually placed on said forms.

2. Manual bookkeeping apparatus comprising in combination a backing board to receive a plurality of separate loose-leaf blank bookkeeping forms perforated along one edge, a row of pegs carried by said board to receive the perforated side of said forms and hold same in predetermined relationship to other forms on the board, a combined column and line guide slidably supported upon said board, means cooperative with said slidable support for temporarily holding same at predetermined equally spaced stations, said column and line guide including a transparent

frame and a plurality of intersecting flexible wires therein between which indicia may be manually placed on said forms.

3. Manual bookkeeping apparatus comprising in combination a backing board to receive a plurality of separate loose-leaf blank bookkeeping forms perforated along one edge, a row of pegs carried by said board to receive the perforated side of said forms and hold same in predetermined relationship to other forms on the board, a combined column and line guide, consisting of a transparent frame and intersecting flexible wires, slidably supported upon said board, said slide support including a pivotal mounting for said column and line guide whereby said guide may be pivotally moved to or from said forms.

4. The combination with a manual bookkeeping apparatus of the class described having a movable clamping bar, of a combined column and line guide slidably and pivotally supported by said bar, said guide consisting of a transparent frame and a plurality of spaced intersecting flexible wires between which entries on a bookkeeping form may be manually made.

5. A manual bookkeeping apparatus of the class described having a movable clamping bar, a combined column and line guide carried by said bar for application to a record sheet, characterized by said guide including an open mesh wire structure longitudinally thereof through which indicia may be made upon said record sheet.

6. A manual bookkeeping apparatus of the class described including a clamping bar and a combined column and line guide, the latter being applicable to a blank record sheet and characterized by being of a transparent frame like structure with the space surrounded by said frame traversed by somewhat flexible wires in opposite directions to simulate line and column spaces in which indicia may be made uniformly upon said sheet intermediate of said wires.

JOHN E. ROSSO.
